UNITED STATES PATENT OFFICE.

WILLIAM A. TURBAYNE, OF NIAGARA FALLS, NEW YORK, ASSIGNOR, BY MESNE ASSIGNMENTS, TO THE SAFETY CAR HEATING AND LIGHTING COMPANY, OF NEW YORK, N. Y., A CORPORATION OF NEW JERSEY.

SYSTEM HAVING COMBINED AUTOMATIC SWITCH AND LAMP REGULATOR.

Application filed April 9, 1920, Serial No. 372,561. Renewed August 12, 1926.

The present invention relates to systems having combined automatic switches and lamp regulators.

More particularly the present invention relates to systems wherein a variable speed generator is used to supply current to a storage battery and a translation circuit in parallel branches, said systems combining in unitary structure the automatic switch and translation circuit regulator which are commonly provided in such systems.

An object of the invention is to provide a novel system involving a combined automatic switch and lamp regulator.

15 A further object is to provide a mechanism which is very sensitive to changes across the translation circuit of a system of the kind referred to above.

20 Further objects will appear as the description proceeds.

Referring to the drawings—

Fig. 1 represents diagrammatically one embodiment of the present invention.

Fig. 2 represents a detail of construction.

25 The numerals 1 and 2 represent electric mains constituting a source of electrical energy. Said mains 1 and 2 may be supplied from a generator, not shown, which may be driven from the car axle of a train or by the engine of a motor car. Said mains 1 and 2 are adapted to deliver current to the storage battery 3 and to the translation circuit 4, which may be connected in parallel branches across said mains 1 and 2. Said 35 translation circuit 4 contains translation devices 4'.

The combined automatic switch and lamp regulating mechanism referred to above includes a magnetic frame comprising the cores 5 and 6, the armature 7 and the armature 8. Cores 5 and 6 preferably lie in parallel relation, the left hand ends being positioned to be bridged by the armature 7, and the right hand ends being positioned to be bridged by armature 8. The cores 5 and 6 and armatures 7 and 8 are adapted to provide what is practically a closed magnetic circuit. The armature 7 is adapted to operate a switch for closing mains 1 and 2 upon the battery 3 and the translating circuit 4 in a manner which will be described hereinafter. The armature 8 is adapted to operate a rheostat 10 in the translation circuit 4, as will be explained later.

55 Mounted upon the cores 5 and 6 are the solenoids 9—9 which are connected in series with one another. One end of these solenoids is connected to the main 1, while the other end of these solenoids is connected to that end of the rheostat 10 which is adjacent to the translating devices 4'. As will be apparent hereinafter, the solenoids 9—9 comprise the operating voltage means for the automatic switch. The automatic switch comprises a movable contact member 11 60 operating in response to the armature 7, which contact member 11 is adapted to engage with the fixed contact member 12. The fixed contact member 12 is connected through solenoid 13 with the translating devices 4' and compressible rheostat 10 to the main 2. Said contact 12 is also connected through the solenoid 14 and storage battery 3 to the main 2. The solenoids 13, 14 and the voltage solenoids 9, 9, are mounted 65 upon the cores 5 and 6 and are wound to operate cumulatively when current is being delivered from the mains 1 and 2 to the storage battery 3 and the translating circuit 4.

70 Armature 8 is biased by the spring 15 to a position away from the ends of the cores 5 and 6. Said armature 8 operates a lever 16 which controls the pressure on the rheostat 10. Said spring 15 normally tends to 75 hold said rheostat in a state of compression, whereby the resistance of said rheostat is a minimum.

75 Figure 2 shows the preferred manner of mounting the solenoids 13, 14, said two 80 solenoids 13, 14 being mounted upon the cores 5 and 6 respectively.

A mode of operation of the described embodiment of the present invention is substantially as follows. When the voltage 95 across the mains 1 and 2 is low, the pull of the solenoids 9, 9 will be of only a small amount and armature 8 will be biased by spring 15 to a position away from the ends of cores 5 and 6. Lever 16 will hold the 100 rheostat 10 in a state of compression at this time, whereby there will be only a minimum of resistance offered to the passage of current from the storage battery to supply the demands of the translation devices 4'. Inasmuch as the resistance of the rheostat 10 is low at this time, the voltage solenoids 9, 9 will be sensitive to changes in voltage across

the mains 1 and 2. When a predetermined voltage is attained across said mains 1 and 2, the solenoids 9, 9 will be sufficiently energized to attract armature 7, thereby causing 5 movable contact 11 to engage with stationary contact 12, closing circuit from the mains 1, 2 to the battery 3 and translation devices 4'. Operation of armature 7 will not only result in the closing of the circuits 10 just referred to, but will accomplish the further purpose of reducing the magnetic reluctance of the magnetic frame comprising cores 5 and 6 and armatures 7 and 8. The parts will be so designed that with the reduction 15 in magnetic reluctance, due to the attraction of armature 7, any voltage in excess of the desired lamp voltage across solenoids 9, 9 will result in the attraction of armature 8, relieving compression of rheostat 10 to increase the resistance in circuit with translating devices 4'. Substantially constant voltage will therefore be held across the translating devices. At such times that the armature 7 is in unattracted position, 20 i. e., when the battery alone is supplying the demands of the translating devices 4', the armature 8 will be unable to operate lever 16, due to the increased reluctance of the frame comprising members 5, 6, 7 and 8. 25 Solenoids 13 and 14 will act as holding coils acting cumulatively with voltage solenoids 9, 9, as long as the voltage across mains 1 and 2 is at or above a predetermined figure. Solenoid 14 will also 30 operate as a releasing coil if the battery should tend to discharge back through mains 1 and 2, functioning in a manner which is well known in connection with automatic switches. Said solenoids 13, 14 will also 35 improve the sensitivity of the lamp regulator for the following reasons. Let it be supposed, for example, that a number of lamps are switched on, whereby there is liable to be caused a momentary drop in 40 voltage on account of the time lag in the regulating means which may be employed at the source of E. M. F. across which the mains 1 and 2 are connected. This time lag, is, of course, particularly pronounced 45 in those systems in which the source is regulated by an external electro-mechanical regulating device. The turning on of more lamps not only tends to reduce the voltage effective on solenoids 9, 9, but also causes 50 a sudden pronounced reduction of current in the series solenoid 14 connected in series with the battery. This reduction of current flow through solenoid 14 is momentarily 55 much greater than the increase in flow through solenoid 13, due to the low internal resistance of a storage battery, so that the combined action of solenoids 9, 9, solenoid 60 13 and battery solenoid 14 produces such a weakening in the magnetic flux that instantaneous and effective regulation is pro-

duced. The throwing off of lamps or anything of this nature which tends to cause an abrupt rise in voltage, produces, of course, opposite results. The arrangement of coils 13 and 14 in separate circuits on the 70 separate legs of the magnet may be departed from without departing from the broader features of the invention but the arrangement shown is preferred for the reason that such arrangement permits choice in the ratio 75 in the number of turns in said coils.

The described embodiment of the present invention has been chosen merely for the purpose of illustration. Many modifications will occur to those skilled in the art. It is intended in this patent to cover all such modifications that come within the scope of the invention as defined by the appended claims.

What I claim as new and desire to secure 85 by Letters Patent of the United States, is—

1. In combination, magnetic members adapted to form a substantially closed magnetic circuit, certain of said members being movable in response to magnetic conditions in said circuit, a source of electrical supply, a storage battery circuit and a translation circuit, a coil responsive to voltage conditions in one of said circuits for magnetizing said magnetic members, means responsive to current flow in said circuits for magnetizing said members, a switch for connecting said source to said circuits, said translation circuit being provided with a variable resistance rheostat, one of said movable members being connected to operate said switch and another of said movable members being connected to operate 95 said rheostat.

2. In combination, magnetic members including two relatively stationary and two relatively movable members adapted to form a substantially closed magnetic circuit, a source of electrical supply, a storage battery circuit and a translation circuit, a coil responsive to the voltage across said translation circuit for magnetizing said magnetic members, means responsive to current flow in said battery and translation circuits for magnetizing said members, a switch for connecting said source to said circuits, said translation circuit being provided with a variable resistance rheostat, one of said movable members being connected to operate 100 said switch, the other of said movable members being connected to operate 105 said rheostat.

3. In combination, a source of electrical supply, a battery circuit, a translation circuit and a combined automatic switch and regulator, the switch element thereof being positioned to connect the source to the battery and translation circuits and the regular element thereof being connected in circuit to 115 120 125 130

regulate one of said circuits, said switch and regulator being provided with a voltage responsive coil, a coil responsive to current flow in said translation circuit, and a coil 5 responsive to current flow in said battery circuit.

4. In combination, a source of electrical energy, a storage battery, a translation circuit, switching means for connecting said 10 source to said battery and said translation circuit, regulating means for said translation circuit, operating means for said regulating means, operating means for said switching means, said switch operating means co-operating 15 with said regulator operating means to increase the operating efficiency thereof.

5. In a system, in combination, a source of electrical energy, a storage battery, a translation circuit, switching means for connecting said source to said battery and said translation circuit, regulating means for said translation circuit, operating means for said regulating means, common controlling means 20 for said switching means and said operating means, the effectiveness of said controlling means to control said operating means being responsive to the operation of said switching means.

6. In a system, in combination, a source of 25 electrical energy, a storage battery, a translation circuit, regulating means for said translation circuit, magnetic operating means for said regulating means, means for changing the reluctance of said operating means, and means operated by said last mentioned means for connecting said source to said battery and said translation circuit.

7. In a system, in combination, a source of 30 electrical energy, a storage battery, a translation circuit, regulating means for said translation circuit, operating means for said regulating means, said operating means being provided with means for preventing operation of said regulating means until a pre-determined voltage is developed across said 35 source, said preventing means operating

upon the attainment of said predetermined voltage to increase the operating efficiency of said regulating means.

8. In a system, in combination, a source 40 of electrical energy, a storage battery, a translation circuit, regulating means for said translation circuit, operating means for said regulating means, said operating means being provided with means for preventing operation of said regulating means until a predetermined voltage is developed 45 across said source, and means responsive to said preventing means for connecting said source to said battery and said translation circuit, said last mentioned means thereafter serving to increase the operating efficiency of 50 said regulating means.

9. In a system, in combination, a source of 55 electrical energy, a storage battery, a translation circuit, a switch for connecting said source to said battery and said translation circuit, regulating means for said translation circuit, operating means for said regulating means, said switch and operating 60 means having electromagnetic operating coils in common, said switch being provided with operating means capable of disabling said first mentioned operating means until said switch is closed.

10. In a system, in combination, a source 65 of electrical energy, a storage battery, a translation circuit, a compressible pile for regulating said translation circuit, voltage means and current means for controlling 70 said pile, switch means for connecting said source to said battery and to said translation circuit, said voltage means and current means being adapted to control said switch means, said switch means being provided with means for ensuring that said pile shall 75 have no regulating action until said switch means is closed.

In witness whereof, I have hereunto subscribed my name.

WILLIAM A. TURBAYNE.
